UNITED STATES PATENT OFFICE.

DANIEL P. CHRISTMANN, OF DELTA, OHIO.

ARTIFICIAL HAND.

1,268,546.

Specification of Letters Patent. Patented June 4, 1918.

Application filed January 31, 1918. Serial No. 214,631.

To all whom it may concern:

Be it known that I, DANIEL P. CHRISTMANN, a citizen of the United States, residing at Delta, in the county of Fulton, State 5 of Ohio, have invented a new and useful Artificial Hand; and I do hereby declare the following to be a full, clear, and exact description of the invention, such as will enable others skilled in the art to which it 10 appertains to make and use the same.

The present invention relates to an artificial hand, and has for its object to provide a device of this character which embodies novel features of construction whereby it 15 can be manipulated in a most effective manner to grasp and lift different articles, as well as to hold a pencil or stylus, thereby enabling a person who has lost his hand to perform practically all kinds of useful work 20 in a very satisfactory manner.

Further objects of the invention are to provide a device of this character which is comparatively simple and inexpensive in its construction, which has no complicated parts 25 which are liable to break or get out of order, which can be readily mounted in position, which can be effectively manipulated with the arm in different positions, and which does not require an excessive amount of skill 30 for its use.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in 40 which:

Figure 1 is a side elevation of an artificial hand constructed in accordance with the invention, showing the jaws in one position, portions being broken away and shown in 45 section.

Fig. 2 is a view looking at the artificial hand from the opposite side, and showing the jaws in a different position.

Fig. 3 is a sectional view on the line 3—3 50 of Fig. 1, showing the pivotal connection between the two members.

Figs. 4 and 5 are end views of the two jaws or arms which are utilized to grip a stylus or pencil.

Fig. 6 is an elevation of an arm having 55 the improved hand applied thereto.

Corresponding and like parts are referred to in the following description and indicated in all the views of the drawings by the same reference characters. 60

Referring to the drawings, which illustrate one embodiment of the invention, the numeral 1 designates an elongated stock which is provided at one end with a threaded stem 2 for attachment to the wrist stump. 65 The opposite end of the stock terminates in a flat circular plate 3 which is offset on one side of the stock and is provided with a central opening receiving a pivot bolt 4. Integral with the circular plate 3 is a pair of 70 substantially radially extending arms 5 and 6, said arms being of the same length and being arranged upon opposite sides of the axis of the hand. The arm 5 is formed with a forwardly curved claw 7, while the arm 75 6 is formed with a rearwardly extending lifting hook 8.

Fitted against the circular plate 3 and pivotally connected thereto by the bolt 4 is a second circular plate 9, the two plates having a combined thickness equal to the thickness of the stock 1 and jaws carried thereby, so that the sides of the artificial hand are substantially smooth and free from annoying projections. Rigid with the plate 9 and 80 projecting from opposite sides thereof are the substantially radial arms 10 and 11, the arm 10 being arranged between the arms 5 and 6 of the fixed plate 3, while the arm 11 is arranged to the rear of the arm 5. The 90 arm 10 is formed with a forwardly extending claw 12 which is adapted to coöperate with the claw 7 of the arm 5 to engage any object which it may be desired to lift, the two claws being indicated on Fig. 2 as 95 brought into coöperative relation. The opposed faces of the arms 10 and 6 are radially disposed so as to come squarely together when the jaws are closed, being formed with a series of transversely extending teeth 13 100 to facilitate the gripping of an object between the same, and being also formed with longitudinally extending grooves 14 which open through the ends of the arms and provide seats adapted to receive and position a 105 pencil or stylus 15 which may be grasped between the jaws.

The arm 11 which is rigid with the pivot plate 9 is hooked forwardly toward the arm 5, as indicated at 16, the inner face of the 110 hooked portion of the arm and the opposed radial face of the arm 5 being provided with

transverse teeth 17 which enable a firm grip to be obtained upon any object positioned between the jaws or arms. This hooked arm 16 enables a door knob or similar round object to be readily grasped by the artificial hand.

A small clip 18 is pivotally connected to the end of the arm 11, said clip being loosely engaged by the end of an operating rod 19 which has a resilient and operative connection with the arm at a point above the elbow so that the artificial hand can be controlled by the relative movements of the fore arm and upper arm. The end of the operating rod 19 is provided with a plunger 20 which telescopes within a tubular casing 21, coil springs 22 being interposed between opposite sides of the plunger 20 and an abutment 23 at one end of the casing and a plug 24 which is screwed removably into the other end of the casing. This plug 24 is intended to be operatively connected to a suitable member 25 upon the upper arm. The operating rod 19 can thus be moved back and forth longitudinally to turn the circular plate 9 on the fixed plate 3.

In Fig. 6 the artificial hand is illustrated as applied to a conventional arm, said arm including a socket A which is secured to the upper arm by suitable means such as the strap C, and which is provided with side bars B. These side bars B are pivotally connected at their lower ends to the side bars D of the lower arm, as indicated at E. The threaded stem 2 is screwed into the swinging end of the lower arm, while the member 25 projects from one of the side bars B of the upper arm, thereby enabling the parts of the hand to be manipulated by moving the fore arm relative to the upper arm. When the plate is rotated in one direction the claws 7 and 12 are swung toward each other and brought into coöperative relation, as indicated by Fig. 2. When the plate is rotated in the opposite direction, the arm 6 is swung toward the arm 10 and the arm 11 swung toward the arm 5. A pencil or like object may then be grasped between the arms 6 and 10, or the arms 11 and 5 may be utilized to grasp a door knob or similar object. Owing to the resilient connection between the operating rod 19 and the upper arm, it will be understood that a considerable amount of relative movement is permitted between the upper arm and fore arm after the jaws or arms have been brought into the desired relation. The tightness with which the object is grasped can also be regulated, since it will be obvious that as one of the springs 22 is placed under increased compression the jaws will be caused to grip the object more tightly, although the grip will always be of a resilient character. The hook 8 of the arm 6 is intended to be used for general lifting purposes, and it will be

readily understood that the handle of the basket or like member can be brought into engagement with this lifting hook without any difficulty.

Having thus described the invention, what I claim as new and desire to secure by Letters Patent, is:—

1. An artificial hand including a stock adapted to be attached to the wrist stump and provided at its outer end with a fixed circular plate, a pair of rigid arms projecting from the fixed circular plate on opposite sides of the axis of the stock, one arm being provided with a forwardly extending claw, a second circular plate fitted rotatably against the fixed plate, a pivot bolt connecting the two plates, a pair of rigid arms projecting from the rotatable plate, one of which extends between the arms of the fixed plate and is provided with a forwardly extending claw adapted to be swung toward the before mentioned claw to grip an article to be lifted, the rear face of the arm having an opposed relation to the other arm of the fixed plate for coöperation therewith to grip an article when the rotatable plate is moved in the opposite direction, the other arm of the rotatable plate being hooked for coöperation with the first mentioned arm of the fixed plate to grasp a round object, and an operating rod connected to one of the arms of the rotatable plate.

2. An artificial hand including a stock adapted to be attached to a wrist stump and provided at its outer end with a fixed circular plate, a pair of rigid arms projecting from the fixed circular plate on opposite sides of the axis of the stock, one arm being provided with a forwardly extending claw, while the other arm has a radially extending forward face which is longitudinally grooved, a second circular plate fitted rotatably against the fixed plate, a pivot bolt connecting the two plates, a pair of rigid arms projecting from the rotatable plate, one of which extends between the arms of the fixed plate and is provided with a forwardly extending claw adapted to be swung toward the before mentioned claw to grip an article to be lifted, the rear face of the arm being radially disposed and provided with a longitudinal groove adapted to coöperate with the before mentioned longitudinal groove of the second mentioned arm of the fixed plate to receive a pencil, the other arm of the rotatable plate being hooked forwardly for coöperation with the back of the first mentioned arm of the fixed plate to grasp a round object, and an operating rod connected to one of the arms of the rotatable plate.

3. An artificial hand including a stock adapted to be attached to a wrist stump and provided at its outer end with a fixed circular plate, rigid arms projecting from the fixed plate, a second circular plate fitted ro-

- tatably against the fixed plate, a pivot bolt connecting the two plates, a pair of rigid arms projecting from the rotatable plate and constructed for coöperating with the arms of the fixed plate to grip different articles as the rotatable plate is swung back and forth to bring different sets of the arms into coöperative relation, an operating rod connected to one of the arms of the rotatable plate, and resilient connecting means for attaching the operating rod to the upper arm of the wearer. 4. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs. 5. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs. 10. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs. 15. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs. 20. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs. 25. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs. 30. An artificial hand including a stock adapted to be attached to a wrist stump and provided at its outer end with a fixed circular plate, rigid arms projecting from the fixed circular plate, a second circular plate fitted rotatably against the fixed plate, a pivot bolt connecting the two plates, arms projecting from the pivot plate and adapted to be swung back and forth into coöperative relation with the arms of the fixed plate, an operating rod connected to one of the arms of the rotatable plate, a plunger at the end of the operating rod, a tubular casing receiving the plunger, and coil springs arranged within the tubular casing and engaging opposite sides of the plunger to provide for relative movement between the operating rod and casing in either direction against the action of one of the springs.

In testimony whereof I have signed my name to this specification in the presence of two subscribing witnesses.

DANIEL P. CHRISTMANN.
